UNITED STATES PATENT OFFICE

FRANK J. SPRAGUE, OF NEW YORK, N. Y., ASSIGNOR TO SPRAGUE SAFETY CONTROL & SIGNAL CORPORATION, OF NEW YORK, N. Y., A CORPORATION OF VIRGINIA

APPARATUS FOR CONTROLLING THE MOVEMENT OF VEHICLES ON RAILROADS

Original application filed April 12, 1927, Serial No. 183,193. Divided and this application filed July 6, 1929. Serial No. 376,400.

This application is filed as a division of my prior application, Ser. No. 183,193 of April 12, 1927, for apparatus for controlling movement of vehicles on railroads, and the subject hereof forms part of the apparatus disclosed in the aforesaid application.

My invention relates to an improvement in automatic train control systems, and particularly to the features known as forestalling and resetting, the former being an operation by which the engineer may, by the performance of a suitable manual act, prevent the coming on of an automatic brake application, and the latter an operation by which the brake controlling apparatus may be restored to normal condition, after which the brakes (if applied) may be released and free running conditions established.

In much of present practice the forestalling and resetting operations are effected by mechanisms differently placed, the forestalling being done in the cab, and the resetting through a switch or other device situated at such an inconvenient point as will require the train to be stopped before it can be used, so as to prevent release of the brakes, applied in response to a track initiated impulse, before the train has come to rest, although sometimes this reset switch is made inconvenient but possibly accessible when the train is moving at slow speeds.

To place some restriction upon the act of forestalling, which unless limited by the condition that a train must be actually braked or has had its speed reduced to some predetermined rate—although present practice and rules actually permit forestalling at any speed and without any pre-application of the brakes—it has been proposed to limit the time period in which the engineer may forestall an automatic brake application when receiving a track impulse. This is done in certain electrically controlled systems by connecting a forestalling switch and circuits so that after manual operation of the switch by the engineer the forestalling circuit will be closed, and the essential circuit will be maintained for only a limited time, the movement of the switch handle initiating a motive force which after a short interval will open the es-

sential circuit, just as the pilot circuits are made and opened in my Letters Patent No. 660,065 on the multiple-unit system of train control.

With this arrangement, the engineer, on approaching a stop indication point within a distance less than he will cover in a predetermined time, which may be anything from a hundred to a thousand feet or more, according to the speed of a train, moves his switch to the forestalling position, closes the forestalling circuit and initiates the motive force, which will open the essential circuit automatically in a predetermined time—say 15 seconds. After passing the stop indication point, if he returns the switch to the normal position within the time period there will be no automatic braking, although some part of the equipment may be responsive. But if the switch is held in the forestalling position for longer than the time period the brakes will come on.

Thus there are three conditions in which the automatic brake application may take place as a result of passing a stop indication point. First, if the engineer does nothing; second, if he forestalls too soon; and, finally, if he holds on too long. Any of these conditions may possibly act adversely as regards train movements.

With the automatic brake application in effect, the amount of braking is made such as to bring the train to a stop, after which the engineer or fireman must get down from the cab, or climb out to a position difficult of access when the locomotive is moving, to reset the brake initiating apparatus, so that the engineer may release the brakes manually.

The main object of thus separating the forestalling and resetting actions, and providing for a time limit is to induce some measure of alertness on the part of the engineer, under possible penalty, and to insure that once the brakes have actually come on automatically the train shall be stopped before the engineer can release them.

There are serious objections to both practices, and specifically to the lack of restriction of the use of a forestalling device, as well as to the necessity for getting out of the cab

to enable the brakes to be released. This latter act cannot be performed at times without serious danger, as in tunnels, snow-sheds and on trestles, or in proximity to passing trains and under conditions of poor visibility.

I desire, therefore, to provide definite limitations upon the act of forestalling, as well as upon the act of resetting, while the timing mechanism for opening the fore-stalling circuit may be omitted entirely. I plan, also, to combine in a single mechanism—operated in the cab—both the fore-stalling and resetting operations, and for compelling, under possible penalty, acknowledgment of the receipt of a brake initiating impulse from the track. This mechanism may conveniently be referred to as an "acknowledging device".

My invention will conduce to safety and convenience, and eliminate delays, while making it possible to impose upon the engineer such precautionary conditions as are essential to safe operation and the maintenance of the fundamentals of automatic train control systems.

The accompanying drawings and specification illustrate my invention as applied to a system of automatic train control which cooperates with the usual type of air brake equipment in whole or in part. It is of course applicable not only to vehicles propelled by steam but to vehicles otherwise propelled. It should be noted that the mechanic, electric and pneumatic devices shown in these drawings serve merely to illustrate the nature of the invention, and thus do not limit it to the construction shown.

In the accompanying drawings which form a part of this application—

Figure 1 is a diagrammatic illustration of the electric circuits of the vehicle-carried equipment of a train control system incorporating my invention.

Fig. 2 is an enlarged sectional view of the sylphon-operated contactor B of Fig. 1.

Fig. 3 is a diagrammatic perspective view of the rotatable contactor mechanism of the acknowledging device F2 of Fig. 1.

Figs. 3a, 3b and 3c are schematic side views of the rotatable contactors 118 and 119 of Fig. 3; Fig. 3a showing relative position of the rotatable and stationary contacts in normal running position, Fig. 3b being an intermediate position of these contacts during operation, and Fig. 3c their final position if the handle of the device is moved to and retained in its operated position.

Relay R represents the governing element of the circuits. This relay is normally energized, its maintaining circuit being the following: From the positive side of the battery H, contactor A, contacts 7, 6, armature 2, and coil of relay R, back to the negative battery. As the maintaining circuit of relay R includes its own armature 2 it is a "stick

relay" which, when once de-energized, cannot be re-energized by way of its normal maintaining circuit.

The contactor A represents an element for changing the electrical condition of the governing element of the circuits, which element is herein illustrated as a stick relay. The contactor A is for convenience illustrated as biased by a spring 18 and is intended to be controlled by track elements. In the specific illustration it is normally held by its spring against its cooperating contact so as to close the maintaining circuit of relay R. However, if an active application track element is passed the armature A is so affected as to open the maintaining circuit of relay R at contact 7.

The word "active" in this connection refers to the condition of the track element which is intended to initiate automatic braking and does not refer to the inherent condition of the track element itself. The term "track element" is likewise employed in its broadest sense irrespective of the type of system, whether continuous or intermittent, to which my invention is applied.

For illustrative purposes the intermittent inductive type of system may be referred to, such, for example, as is shown in my British Patent No. 18,213 of 1915, and British Patent No. 149,922, or my U. S. Patent No. 1,669,165, of May 8, 1928. In each of these the track element when "active" may result in changing the condition of a controlling circuit from normal to operative condition. More precisely in the specific illustration herein the contactor A may be considered as opened by magnetic attraction from an active track element.

The stick relay R normally maintains its armature 1 against a contact 4 in the normally closed circuit of an electro-pneumatic vent valve V.

The vent valve V represents the connecting member between the electric and pneumatic parts of the vehicle-carried equipment, de-energization of which valve initiates an automatic brake application. Various pneumatic equipment may be used in connection with my invention—for instance, the one described in my previously referred to application, Ser. No. 183,193 of April 12, 1927.

The vent valve is energized through the following circuit: from the positive side of battery H, through speed-controlled contacts 130, 131—which as later explained are normally electrically connected by a cylindrical contact 133—to the coil 20 of the vent valve and contact 4 and armature 1 of relay R, back to the negative side of the battery. The circuit of the coil 20 is normally closed, provided, as more fully explained later on, the speed of the train does not exceed a predetermined maximum value.

As mentioned previously, when the stick

relay R is de-energized, as happens when passing over an active application track element, it cannot be re-energized by way of its normal maintaining circuit, even if such track element is passed and contactor A has assumed its normal position; such re-energization can only take place by way of re-energizing circuit. These circuits, and the devices associated therewith, will now be described. The devices just referred to are an acknowledging device F2, a speed-governor M1, and a sylphon-operated contactor B.

The acknowledging device F2 is illustrated in Figs. 3, 3a, 3b and 3c, the normal position being shown in Figs. 3 and 3a, an intermediate position in Fig. 3b and the final position prior to automatic return of the device to normal in Fig. 3c. Two cylindrical contactors 119 and 118 are mounted on a shaft 109. The contactor 119 is fixed to the shaft. The contactor 118 is not rigidly fixed to the shaft but is connected therewith by a spiral spring 117 located within an annular space in the contactor. This spring tends to move the contactor towards its operative position, but normally the contactor is held in inoperative position by engagement of a rod 121 affixed to the contactor 118 and projecting laterally therefrom with one end in an annular slot 122 formed in the contactor 119. A handle 105 is provided on the shaft 109, so that, when 105 is manually operated, the contactor 119 rotates away from the rod 121 and releases the contactor 118 for rotation under the influence of its spiral spring 117. The rotation of the contactor 118 is governed by a clock-work mechanism 120, schematically indicated in Fig. 3, so that it proceeds evenly and at a lower rate than the normal manual rotation of the contactor 119. The surface of contactors 118 and 119 is of insulating material except for insulated strip contacts y2 and y1 respectively. These strip contacts y2 and y1 are so positioned in respect to the stationary contacts 12, 13, 140 and 150 that electric connection between contacts 12 and 13 and between contacts 140 and 150 respectively is normally broken.

When the handle 105 is moved to its operated position the strip contact y1 bridges contacts 140 and 150. At the same time contactor 118 being released starts to rotate. Shortly after the commencement of this rotation the strip contact of y2 bridges contacts 12 and 13 as shown in Fig. 3b. However, after a certain time lapse the strip contact y2 leaves contact 13 and the breaking of the connection between contacts 12 and 13 is again effected. It is thus only in an intermediate position of contactor 118 that the series bridging of contacts 12, 13, 140 and 150 is brought about. The length of time that this continues is governed by the clock-work 120 and is at the option of the road adopting this system. It should be noted

that contacts 12 and 13, and 140 and 150 are both normally open and that on completion of rotation of contactor 118 contacts 12 and 13 are open; further that contacts 140 and 150 are only made on complete manual movement of the handle 105. This arrangement nullifies the effect of operating the acknowledging device in the event of failure, for any reason, of the contactor 118 to move and serves as a further check in preventing intended operation by tying down the handle.

The centrifugal governor M1 has attached to its movable head a cylindrical circuit breaker 135, the right hand surface of which is of insulation 134 and the left hand surface of conductive material 133. Three brushes 130, 131 and 132 are provided for cooperation with the circuit breaker 135. Brush 130 is connected with the positive side of battery H; brush 131 is a high-speed brush in the circuit of the coil 20 of the vent valve V; and brush 132 is a low-speed brush in the forestalling and resetting circuits of the stick relay R. On movement to the left of the circuit breaker 135 by the speed governor M1 the insulation 134 first reaches the low-speed brush 132 and then the high speed brush 131. The speeds at which the circuits controlled by these brushes are thus broken are matters of adjustment to suit the requirements of the road adopting the system.

The sylphon-operated contactor B comprises a housing 84 in which is mounted a sylphon 83 normally under equal air pressures inside and out. The sylphon carries a cap 82 to which is attached a stem 81 which slidably extends through the housing (by means of a substantially air-tight bushing 85) and supports an insulated disc contact 3. The stem 81 is surrounded by an adjustable coil spring 80 which abuts against the bushing and the cap and normally holds the disc contact 3 in its lowermost position. Pneumatic connection is made with the sylphon-operated contactor by means of pipe c which communicates with the chamber c4 inside the sylphon, and pipe b1 which communicates with the chamber b4 outside the sylphon. The operation of the sylphon-operated contactor depends upon a differential of pressure in the chambers c-4 and b-4.

The differential of pressure in the chambers c-4 and b-4 is obtained when an automatic brake application takes place. To achieve this various apparatus can be used as, for instance, described in my co-pending application Ser. No. 183,193 of April 12, 1927, and, as governing pressure, for instance equalizing reservoir or brake pipe pressure may be used, although as described in my previously referred to application other governing pressures may be employed.

Normally both chambers are maintained at equal pressure, but in case an automatic

brake application takes place a pressure difference between chambers $c-4$ and $b-4$ is established with the consequent upward motion of contact 3.

- 5 Two lower contacts 10 and 11 are normally connected with each other by the disc contact 3 which connection, however, is broken when in case of an automatic brake application contact 3, due to the differential of pressure in chambers $b-4$ and $c-4$, is moved upwardly. When this pressure difference has reached a certain value, depending upon the adjustment of the spring 80 the contact 3 bridges a pair of upper contacts 8 and 9.
- 10 15 The vent valve V is provided with a normally attracted armature 101 which, when the vent valve V is de-energized, bridges a pair of contacts 103 and 103'.

20 A warning device which may be audible, visible, or both, and which is represented in the drawing by the audible signal K, is provided. When the relay R is deenergized and drops its armature 1, the circuit of signal K is closed as follows:

25 From plus battery, through signal K, contact 5 and armature 1 back to negative battery.

30 A time delay is preferably provided between the de-energization of the vent valve and the automatic application of the brakes. This time delay may be varied from the fraction of a second to several seconds, depending on the requirements. There are many known ways to provide such a time delay, as, 35 for instance, by the means described in my above referred to application Ser. No. 183,193 of April 12, 1927.

40 Under normal conditions the stick relay is energized and its armatures 1 and 2 are attracted. The vent valve is thus energized unless the speed exceeds the maximum speed limit, in which latter case the high-speed brush 131 contacts with the insulated portion 135 of the speed governor and the vent valve 45 is de-energized. This causes an automatic application of the brakes; however, as soon as the train reduces its speed below the maximum speed limit—the relay R not having been de-energized—the vent valve is automatically re-energized and the brakes can be released.

45 However, if an active application track element is passed the relay R is de-energized and can only be re-energized by closing one 55 of its re-energizing circuits which shall be now discussed:

There are two re-energizing circuits for the stick relay, one being the forestalling circuit and the other the resetting circuit.

60 Both the forestalling and resetting circuits are partly closed upon manual operation of the acknowledging device; however, completion of the forestalling circuit can only take place provided no automatic braking has been 65 initiated, while completion of the resetting

circuit can only take place if a brake application of a predetermined value has taken place.

Both the forestalling and resetting circuits go from the plus side of the battery H through the battery brush 130 and low-speed brush 132 of the speed governor (these two brushes being electrically connected by the contact 133 provided the speed of the train is below the low-speed limit) the contacts 103 and 103',—which are bridged only in case the vent valve V is de-energized,—to the contacts 14—15 and 12—13 of the acknowledging device. At this point the forestalling and reset circuits separate, the forestalling circuit going through contacts 10 and 11 of the sylphon-operated contactor which are normally bridged by contact 3, while the resetting circuit goes through the normally open contacts 8 and 9 of the sylphon-operated contactor. Contacts 8 and 10 are interconnected and from here the two circuits again reunite and go through relay R to the negative side of battery H.

From the foregoing it is apparent that to re-energize the relay R after it has been de-energized the following conditions have to be fulfilled: 1. Contact between battery brush 130 and the low-speed brush 132 through contactor 133 must be established, i.e., the speed of the train must be below the low-speed limit. 2. The armature of the vent valve V must be dropped so as to bridge contacts 103 and 103'. 3. Both pairs of contacts, 12—13 and 14—15 of the acknowledging device F2 have to be bridged by segments y_2 and y_1 , respectively. 4. Either contact pair 10—11 or contact pair 8—9 must be bridged by disc contact 3.

As contacts 10 and 11 are bridged by the disc contact 3 as long as the air pressures in chambers $b-4$ and $c-4$ are equal, as previously stated, this implies that no brake application has taken place. Forestalling on the part of the engineer thus will only be effective if aside from the conditions under 1 to 3 being fulfilled, such operation takes place before an automatic brake application has started.

55 Contacts 8 and 9 of the sylphon-operated contactor are bridged by disc contact 3 if a predetermined amount of braking—depending on the adjustment of spring 80—has taken place, this being the requirements for resetting aside from the requirements mentioned under 1 to 3.

In operation, upon passage of an active track element, relay R is de-energized, thus causing armature 1 to drop which energizes audible signal K. This warns the engineer of the danger conditions ahead of the train and advises him of an automatic brake application being effected unless forestalling is undertaken by him.

60 Assume now that the engineer is not pre-

pared to heed such warning or is incapacitated to do so; an automatic brake application will then occur.

However, if the engineer is alert and wishes to take advantage of the forestalling privilege, upon receipt of the warning signal he immediately operates forestalling device F2 and as armature 101 bridges contacts 103—103' (due to de-energization of the vent valve) 10 the relay R will be re-energized, provided the speed of the train is below its low-speed limit, as an automatic brake application not having started, contacts 10 and 11 are bridged by disc contact 3. Re-energization of relay 15 R re-establishes the energizing circuit of the vent valve.

While the low-speed contact 132 and the check contacts 103—103' of the vent valve are inserted in the forestalling circuit herein 20 illustrated, provision of such contacts is optional and these contacts may be omitted if so desired.

If the engineer has not forestalled and an automatic brake application has taken place, 25 the engineer, to restore the equipment to normal, has to wait until a fixed brake application—amount of which is determined by the adjustment of spring 80—has taken place, after which operation of the acknowledging 30 device F2 will re-energize relay R, provided that the speed of the train is below its low-speed limit. Re-energization of relay R re-establishes the energizing circuit of the vent valve.

25 While the low-speed contact 132 and vent valve check contacts 103—103' are inserted in the reset circuits here illustrated, these features are optional and can be omitted if so desired.

40 As previously stated, contact 3 of the sylphon-operated contactor is moved upon a differential pressure in chambers *c*—4 and *b*—4. Such difference in pressure will always take place in the case of automatic 45 brake application but, if so desired, arrangement can be made that it also take place in case of a manual brake application, in which case the resetting will depend on the sum of the automatic and manual brake applications.

50 Various modifications both in regard to the circuits as well as the physical embodiment of the devices may be employed without deviating from the spirit of my invention, and no undue limitation should therefore be deduced from the specific illustration given but the appended claims should be construed as broadly as possible in view of the prior art.

What I claim as new and desire to secure by Letters Patent is:

55 1. In a train control system, car carried equipment comprising a manually operable device having two extreme inactive and inoperative positions and a zone of intermediate brake-preventing positions, said device being normally maintained in one of its inactive

positions, and when placed in an operative position passes intermediate brake-preventing positions and if maintained in this operative position assumes the second inactive position.

2. In an automatic train control system, train-carried apparatus comprising brake-controlling means normally inactive, and when active causing an automatic application of the brakes, a manual device normally in inoperative position, said device when actuated assuming a brake-preventing position for a limited time only, after which it assumes a second inactive position which neither causes nor prevents an application of the brakes.

3. In an automatic train control system, brake-controlling means normally inactive, and when active causing an automatic application of the brakes, and a manually operable mechanism having two inactive and inoperative extreme positions and an intermediate brake-preventing position, said manual device being normally in one of its inactive positions and when operated assuming a brake-preventing position for a limited time, after which it assumes the second inactive position.

4. In an automatic train control system, brake-controlling means, normally inactive but when active causing an automatic application of the brakes, a manually operable mechanism having inactive positions and a zone of brake-preventing positions, said manual device being normally in an inactive and inoperative position, and when operated passing the brake-preventing zone, after which it reassumes a second inactive position.

5. In a train control system of the permissive type, a normally energized electro-responsive brake controlling device, brake-applying means normally inactive and rendered active upon de-energization of the electro-responsive device, a mechanism comprising two normally open contactors, an auxiliary circuit for re-energizing the electro-responsive device including said two normally open contactors, manual means to close one of said contactors and means to automatically close the other contactor upon actuation of the manual means, said automatically closed contactor re-opening after a predetermined time.

6. In a train control system of the permissive type, an electro-responsive brake-controlling device normally energized, said electro-responsive device having a normal maintaining circuit and an auxiliary circuit, said auxiliary circuit serving to re-energize the electro-responsive device after its de-energization, a manually operable device comprising two rotatable contactors, both of said rotatable contactors being normally open and assuming a closed position upon operation of the device, to re-open after a predetermined time following operation of said

mechanism permitting closing of the auxiliary circuit.

7. In an automatic train control system, car-carried equipment comprising brake-applying means and two air-operated contacts, one normally closed and the other normally open, a speed governor having a plurality of speed controlled contactors, a combined forestalling and resetting device, said device 5 permitting, by identical manual operation, the prevention of an automatic application of the brakes provided the normally closed air-operated contact is closed, and the release of an automatic brake application provided 10 the normally open air-operated contact is closed, but not preventing a brake application and not permitting a release of the brakes 15 if a speed controlled contactor is open.

8. In a system for automatic train control, 20 the combination of train-carried brake-applying means and trackway devices transmitting an impulse to the train-carried means whenever danger conditions exist, two air-operated contacts, one normally closed and 25 the other normally open, it being possible to close only one of the two contacts at a time, a speed governor including a low speed and a high speed contact, an acknowledging device, said acknowledging device permitting, 30 by identical manual operation of same, the prevention of automatic application of the brakes due to an impulse received from the track provided the closed air-operated contact and the low speed contact of the speed 35 governor are closed, and the release of an automatic brake application provided the open air-operated contact and the low speed contact of the speed governor are closed, said acknowledging device not preventing an automatic 40 application of the brakes if the high speed contact of the speed governor is opened.

9. In a train control system, car carried equipment comprising an electro-responsive device and an auxiliary energizing circuit 45 for said device, a manually operable device comprising two contactors in series connection, said contactors forming part of the auxiliary circuit, an actuating member for said device having a normal and an operative 50 position whereby in the normal position of the member both contactors are open and upon operation of said member one contactor is immediately closed and remains closed as long as said member is held in the operative 55 position, the other contactor being closed after a short interval of time and remaining closed for a longer interval and again re-opening thereafter, both contactors being opened immediately when said member is 60 returned to its normal position.

10. In a train control system, an electro-responsive device and an auxiliary circuit therefor, a forestalling device comprising a spring biased shaft, an operating handle 65 therefor, and two rotatable contactors in se-

ries connection, said contactors forming part of the auxiliary circuit, one of said contactors being rigidly fixed to the shaft, the second contactor being loosely connected with the shaft by resilient means, a member connecting the two contactors and preventing the second contactor from rotating when the first contactor is in its normal position, a clock-work mechanism to rotate the second contactor, whereby manual rotation of the shaft 70 by means of the handle causes rotation of the first contactor and the release of the second contactor, which is thereby rotated by the clockwork, said contactors normally assuming a position to open the auxiliary circuit and when rotated close this circuit for a 75 limited time.
